UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

REED ARTICLE AND METHOD OF MAKING THE SAME.

Application filed July 13, 1921. Serial No. 484,394.

To all whom it may concern:

Be it known that I, MARSHALL B. LLOYD, a citizen of the United States, and a resident of Menominee, county of Menominee, and State of Michigan, have invented a certain new, useful, and Improved Reed Article and Method of Making the Same, of which the following is a specification.

My invention relates generally to the production of woven reed articles by the general method disclosed in my prior Patents Nos. 1,243,079, 1,243,080, 1,243,081 and 1,243,082, that is to say to a reed article which is composed in part of the frame and in part of a woven reed fabric of the kind defined in my former patents, and which embodies a reed or reed-like fabric formed independently of the frame and thereafter applied thereto. More specifically, my invention relates to the production of woven reed articles from strips of fabric from which it is desired to produce tubular articles.

In making articles embodying therein an independently woven reed fabric, i. e. a stake and strand fabric whether of the natural reed or so-called fibre reed, I find it highly desirable to affix metallic binder strips to the edge portions of the fabric. These metallic binder strips serve a number of very useful and important purposes, such for example as preventing disintegration of the fabric, in facilitating manipulation of the fabric, and in making easy the application of the fabric to the frame. Such metallic edge binders, however, as heretofore used, are objectionable in that their presence is readily detected and serve to mar the beauty of the article. Since reed articles are designed quite as much for beauty as for utility this is a serious objection.

It is an object of my invention to provide a reed article and a method of making the same wherein a metallic edge binder can be successfully used and, at the same time, in the completed article, shall be wholly invisible.

My invention also consists in an article of manufacture, and in the steps, acts and stated sequence thereof whereby the above named objects, together with others that will appear hereinafter are attainable, and

my invention will be more readily understood by reference to the accompanying drawings, which illustrate what I consider at the present time to be the preferred embodiment thereof.

In said drawings:

Fig. 1 is a view of a piece of woven reed or reed-like fabric having metallic edge binders thereon.

Fig. 2 is an enlarged sectional view substantially on the line 2—2 of Fig. 1.

Fig. 3 is a view of the fabric shown in Fig. 1 but with one of the metallic edge binders folded back upon one side of the fabric.

Fig. 4 is a view illustrating the next step in the operation of producing the article, shown in Fig. 6.

Fig. 5 is an enlarged sectional view substantially on the line 5—5 of Fig. 3.

Fig. 6 is a perspective view of a completed article of manufacture formed in accordance with my invention; and

Fig. 7 is an enlarged sectional view substantially on the line 7—7 of Fig. 6.

The fabric which is shown in the drawings may be woven in any desired manner and while it is a stake and strand fabric, it may be composed either of the natural reed, fibre reed or the like. It comprises the typical spaced stakes 1, over and under which filler strands 2 are woven. To the ends of the fabric are affixed metallic binder strips 3 and 4. These binder strips, as is well shown in Figs. 2 and 5, are U-shaped in cross-section, thus forming a channel for the reception of the ends 2' and 2'', respectively, of the filler strands. These metallic edge binders are firmly pressed upon the filler strands and therefore tightly grip them and positively prevent any loosening of the fabric or displacement of the contiguous stakes.

As by way of illustration and not by way of limitation I have depicted the manufacture of a tray, the vertical outer wall of which is tubular in form and which is manufactured from the flat strip of woven fabric previously described.

After affixing the metallic edge binders to the fabric I fold the binder strip 3 backwardly toward one face of the fabric and the binder strip 4 backwardly toward the

opposite face. In folding these back, however, they are not tightly pressed against the fabric, but are slightly separated to form intermediate spaces 5 and 6, respectively, which spaces are substantially the thickness of the binder strips.

The difference between Figs. 3 and 4 is that Fig. 4 is slightly enlarged and also shows the upper part of a portion of a strip 10 cut to form the undulatory line marked 7 which is purely for ornamental purposes.

The strip of fabric is now in condition to be bent or shaped into tubular form which is accomplished by bringing the ends of the 15 fabric bearing the metallic binder strips 3 and 4 into contiguous relation. Assuming the parts to be in the condition shown in Fig. 5, the fabric would be bent in the direction of the arrows and the binder strips 20 brought to slightly overlapping position and then hooked one into the other, being the condition indicated in Fig. 7. By then tightly pressing the parts together they are 25 locked against all danger of separation and, at the same time, the metallic portions are entirely hidden from view. The article 30 then presents the appearance of an endless or tubularly woven fabric. Articles can be produced in this manner very quickly and at low cost and at the same time are admirably adapted for the purpose intended. The quality of durability does not in any 35 sense affect adversely the ornamental appearance of the device, which is so much desired in articles composed of woven reed.

It will be understood that the fabric is secured to the frame 8 but since this may be accomplished in well-known manner no description will be given.

40 The cross partitions 9 and 10 and the bottom 11 form no part of the present invention and have been illustrated merely to show the article in completed form.

I claim:

45 1. The herein described method of producing woven reed articles of tubular form from non-tubular fabric that consists in providing a non-tubular piece of woven reed fabric or the like, securing metallic binder strips to opposite end portions thereof, 50 forming the fabric to tubular shape, meantime folding one metallic binder strip backwardly toward one face of the fabric, and

folding the other metallic binder strip backwardly toward the opposite face of the fabric, and in interlocking the binder strips 55 one with the other.

2. The herein described method of producing woven reed articles of tubular form from non-tubular fabric that consists in providing a non-tubular piece of woven reed 60 fabric or the like, securing metallic binder strips to opposite end portions thereof, forming the fabric to tubular shape around a frame, meantime folding one metallic binder strip backwardly toward one face of the fabric, and folding the other metallic binder strip backwardly toward the opposite face of the fabric, and in interlocking the binder strips one with the other.

3. The herein described method of producing woven reed articles of tubular form from non-tubular fabric that consists in providing a non-tubular piece of woven reed 65 fabric or the like, securing metallic binder strips to opposite end portions thereof, forming the fabric to tubular shape, meantime folding one metallic binder strip backwardly toward one face of the fabric, and folding the other metallic binder strip backwardly toward the opposite face of the 70 fabric, and in interlocking the binder strips one with the other, the binder strips being of such size and being folded back such a distance that when interlocked the stakes are substantially uniformly spaced throughout.

4. The herein described method of producing woven reed articles of tubular form from non-tubular fabric that consists in providing a non-tubular piece of woven 75 reed fabric or the like, securing metallic binder strips to opposite end portions thereof, forming the fabric to tubular shape, meantime folding one metallic binder strip backwardly toward one face of the fabric, 80 folding the other metallic binder strip backwardly toward the opposite face of the fabric, both binder strips being folded back a distance sufficient to hide them when the fabric is viewed from the end, and in interlocking the binder strips, one with the other.

In testimony whereof, I have hereunto set my hand, this 30th day of June, 1921.

MARSHALL B. LLOYD.
